CLAIM

The ornamental design for a CD rack, as shown and described.

DESCRIPTION

FIG. 1 is a top perspective view of a CD rack embodying my new design;

FIG. 2 is a front elevational view thereof, the rear elevational view being a mirror image thereof;

FIG. 3 is a left side elevational view thereof, the right side elevational view being a mirror image thereof;

FIG. 4 is a top plan view thereof; and,

FIG. 5 is a bottom plan view thereof.

The broken lines are for environmental purposes only and form no part of the claimed design.
